PIPE CLEANER

George W. Cottrell, 430 Amapola Lane,
Los Angeles, Calif.

Filed Dec. 9, 1958, Ser. No. 53,709

Term of patent 14 years

(Cl. D85—7)

FIG. 1

FIG. 2

FIG. 3

FIG. 4

Fig. 1 is a top perspective view of a pipe cleaner, showing my new design;

Fig. 2 is a top plan view;

Fig. 3 is a side elevational view; and

Fig. 4 is a bottom perspective view thereof.

The broken line showing of a pipe and a portion of an air hose in Fig. 1 is for illustrative purpose only.

I claim:

The ornamental design for a pipe cleaner, substantially as shown and described.
